PREPARATION OF PHYTOSTEROL
GLUCOSIDES

David P. Langlois, Decatur, Ill., assignor to A. E. Staley Manufacturing Company, Decatur, Ill., a corporation of Delaware

No Drawing. Application July 19, 1940,
Serial No. 346,407

14 Claims. (Cl. 260—210)

The present invention relates to the recovery of glucosides and relates in particular to the production of glucosides of the phytosterol type from natural vegetable oils.

Glucosides of this type are practically universal constituents of natural vegetable oils, but considerable difficulty has been encountered in their recovery from the oil. It has been suggested to recover the phytosterol glucosides from oil-bearing substances by contacting the oil with an adsorbent such as activated alumina. This and the other known methods of recovery have not been satisfactory and a principal object of the present invention is the provision of a method by which phytosterol glucosides may be recovered easily and economically from oil-bearing substances.

A further object of the invention is the provision of a phytosterol glucoside recovery process which includes the treatment of a natural vegetable oil with a water solution of an alkali such as sodium hydroxide, the amount of the alkaline solution being around 3 or 4 times greater than that required to neutralize the free fatty acid content of the oil, centrifuging the alkali-treated oil to separate a soap-containing fraction, and acidulating this fraction to provide a three-phase mixture from which the glucoside may be isolated.

A still further object of the invention is the separation or recovery of phytosterol glucosides from refinery foots obtained from a raw vegetable oil.

Various types of vegetable oils are used extensively in the production of edible fats, soap and the like. Generally these oils are produced by pressing the seed from which they are obtained, this pressing operation being effective to liberate a crude oil containing substances other than triglycerides. Among the other substances present in the crude oil are phosphatides, glucosides, and certain unsaponifiable substances, each of these classes of materials being present in relatively small quantities which makes their recovery or separation from the triglycerides generally difficult.

The glucosides in general have been isolated or recovered from the oil only in quantities sufficient for identification or laboratory experimentation. Phytosterols are of considerable value in the synthesis of various important biological compounds, but their use in this connection has been inhibited by the lack of a suitable supply of the material.

In accordance with the present invention glu-

cosides from which phytosterol may be produced are recovered from oil-bearing substances in substantial quantities and at a relatively low cost.

The process involves the treatment of a raw vegetable oil with a small quantity of an aqueous solution of sodium hydroxide. While the amount of the alkali solution and its concentration may vary to a considerable extent, it is preferred to employ a quantity of the solution somewhat in excess of that necessary to neutralize the free fatty acid content of the raw oil. In carrying out this alkali treatment the alkali solution may be added to the oil at a temperature of around 150° F. and the mixture may be agitated for a period of time sufficient to effect neutralization of the free fatty acid content of the oil and to expend the alkali.

Following the alkali treatment the oil is passed through a centrifuge of any suitable type, and as a result of the centrifuging there is separated a soapy, water and oil mixture of a volume which may represent a loss of approximately 4 per cent of the oil.

This soapy fraction contains the soap resulting from the neutralization of the free fatty acid content of the oil by the alkali and the soap which may have been produced by the slight excess of alkali in saponifying neutral oil. Additionally, there will be present a small quantity of neutral oil.

The soapy fraction further will be found to contain a high concentration of phytosterol glucosides as well as some phosphatides, glycerine and water. It is possible to make an effective separation of the phytosterol glucosides from the soapy fraction. This separation is based upon the acidulation of the soapy fraction. In carrying out this acidulation a sufficient quantity of an acid such as sulfuric acid may be added to the mixture to provide a pH of between about 2 and 5. Steam may be passed through the acidulated mixture for a short time until there is observed a break in the emulsion. Upon standing, the acidulated mixture separates into three layers.

The top layer consists primarily of free fatty acids and the bottom layer is composed principally of water, glycerine and dissolved salts. The center layer consists of an emulsion containing a high concentration of the phytosterol glucoside. The top and bottom layers may be siphoned off, and the phytosterol glucosides then may be recovered from the middle layer by the addition of a sufficient quantity of alcohol to break the emulsion into two phases. The quantity of alcohol required for this operation may be

about twice the amount by weight of the middle layer.

Upon addition of the alcohol to the middle layer there separates a solid phase which contains the phytosterol glucosides and certain alcohol insoluble salts. The phytosterol glucosides are filtered off and the salt may be removed by washing with water.

The soapy fraction recovered by the centrifuging step comes within the class of degumming foots normally produced in the refining of raw vegetable oils. I have found that this class of materials is a rich source of phytosterol glucosides which makes their commercial recovery feasible. Vegetable oil foots may be produced simply by allowing the oil to stand for the time necessary for the separation of tank settling. Water washing of oil also results in the separation of foots from the oil. Generally, though, the foots are produced by an alkali refining process of the type described above, and separation of the foots produced by the alkali treatment may be by settling or centrifuging. The strength of the alkali solution may vary widely, as is well known in oil refining practice. Carbonates, silicates, phosphates and other alkaline materials may be employed in the alkali refining process for the separation of the foots from the oil. The oil-insoluble foots contain relatively large amounts of phytosterol glucoside, regardless of the particular method employed for inducing the separation of the foots from the oil. Generally the foots will contain residual quantities of neutral oil which are separated from the main body of the oil with the removal of the foots. Regardless of the particular treatment of the oil incident to separation of the foots, the treatment of the foots for recovery of phytosterol glucosides will follow substantially the procedure given herein.

In a preferred embodiment of the invention the foots are subjected to a further treatment with an additional quantity of alkali to completely saponify the residual neutral oil contained in it. After the substantially complete saponification of the oil the foots are treated with an acid in the manner described before to provide a pH of from 2 to 5 and the recovery of phytosterol glucosides is affected as referred to above. This further alkali treatment is effective to hydrolyze practically all of the phosphatides present in the foots and this elimination of the phosphatides is of value in the subsequent effective separation of phytosterol glucosides.

As an example of the operation of the process 3,000 pounds of soybean oil were fairly mixed with 135 pounds of 14° Baumé (9.5 per cent) caustic soda solution. The mixture was agitated in mixing tanks to insure complete neutralization of all of the free fatty acids. It then was run to a centrifuge where the soapy residue was separated from the oil. The amount of the soapy fraction recovered was 240 pounds.

This residue then was run into a tank and diluted with a small amount of water equal to about 50 pounds. Then 58 pounds of 40° Baumé caustic soda solution was added and the mixture was brought to the boiling point by steam injection. After 2 hours boiling no further change was noted in the free alkali of the mixture and the heating operation was suspended.

Without cooling the soapy fraction, the sulfuric acid was added in a quantity sufficient to acidulate the mixture to a pH of 3.5. Steam again was passed through the mixture until a definite sign of a break in the emulsion was observed. The

steam then was turned off and the mixture was allowed to stand while cooling. After 16 hours the mixture had separated into three distinct layers. The top oily layer was siphoned off and the bottom water layer also was siphoned off, the middle layer being allowed to remain in the tank. To this remaining middle layer was added 20 gallons of alcohol, the mixture being thoroughly stirred during the addition of the alcohol. As a result of the addition of the alcohol, the mixture separated into a solid phase and a liquid phase. The liquid was removed by filtration and the remaining solid phase was washed with about 5 gallons of alcohol. After drying the resulting solids it was found that the solids weighed 9 pounds of which 4.5 pounds were crude glucoside and 4.5 pounds were water-soluble salts. By washing with water and centrifuging there was recovered 4.5 pounds of phytosterol glucoside having a melting point of between 270° and 275° C.

This relatively pure phytosterol glucoside may be hydrolyzed to produce phytosterol. Conventional methods of hydrolysis may be employed for this purpose. For example, the 4.5 pounds of phytosterol glucoside may be suspended in 9 gallons of alcohol containing 1.5 pounds of hydrogen chloride, and the solution refluxed for several hours until the glucoside completely dissolves. The mixture then may be filtered hot to remove insoluble materials and then allowed to cool. On cooling, the phytosterol crystallizes out and is filtered off.

As before stated, glucosides may be recovered from the various vegetable oils in the manner described herein. Drying oils such as linseed oil, semi-drying oils such as soybean oil, and non-drying oils such as corn oil are other examples of oils which may be treated. Cottonseed oil and the like also may be treated in accordance with the process. Soybean oil is a preferred material from which to recover the glucosides.

It will be recognized that many changes in and additions to the process described herein for purposes of explanation may be made without departing from the scope of the invention as defined in the appended claims.

I claim:

1. The process of producing phytosterol glucosides, which comprises subjecting a vegetable oil to a neutralizing treatment to neutralize the free fatty acid content of the oil, separating the resulting soapy fraction from the oil, acidulating the soapy fraction and heating the same, allowing the acidulated fraction to stand to produce an upper fatty acid layer, a bottom layer, and a middle layer containing phytosterol glucosides and precipitating phytosterol glucosides from the resulting middle layer.

2. The process of producing phytosterol glucosides, which comprises subjecting a vegetable oil to a neutralizing treatment to neutralize the free fatty acid content of the oil, separating the resulting soapy fraction from the oil by centrifugal action, acidulating the soapy fraction and applying heat thereto, allowing said fraction to stand to provide a three-phase mixture having an upper fatty acid layer, a lower water layer, and a middle layer containing phytosterol glucosides, and precipitating phytosterol glucosides from said middle layer.

3. The method of recovering phytosterol glucosides, which comprises subjecting a raw vegetable oil containing said glucosides to a neutralizing treatment to neutralize the free fatty acid content of said oil and to saponify a small quan-

ity of neutral oil, subjecting the oil to centrifuging to produce a soapy fraction containing neutral oil, soap, phosphatides, glucosides and water, subjecting the soapy fraction to a further neutralization treatment, acidulating the soapy fraction to a pH of between 2 and 5 and heating the same, allowing the fraction to stand to produce a liquid mixture capable of separating into an upper fatty acid layer, a bottom water layer, and a middle glucoside-containing layer upon standing, and precipitating phytosterol glucosides from the middle layer.

4. The process of recovering phytosterol glucosides from vegetable oils containing the same, which comprises subjecting the oil to treatment with a relatively dilute alkaline solution in a quantity sufficient to neutralize the free fatty acid content of the oil and to saponify a small quantity of the oil, subjecting the oil to centrifugal action to remove a soapy fraction containing soap, neutral oil, phosphatides, phytosterol glucosides, and water, subjecting the soapy fraction to further treatment with an alkali to hydrolyze said oil and said phosphatides, acidulating the soapy fraction to a pH of between 2 and 5, allowing the acidulated fraction to stand to produce an upper fatty acid layer, a bottom water layer, and a middle layer containing phytosterol glucosides and inorganic salts, recovering said middle layer, treating said middle layer with alcohol to precipitate said glucosides and inorganic salts, and washing the precipitate to remove said salts.

5. The method of producing glucosides, which comprises acidulating vegetable oil refinery foots and applying heat thereto, allowing said acidulated foots to stand to produce an upper fatty acid layer, a bottom aqueous layer, and an intermediate layer, separating said intermediate layer, and treating said intermediate layer to precipitate phytosterol glucosides.

6. The method of producing glucosides, which comprises acidulating soybean oil refinery foots to a pH of between 2 and 5 and heating the same, allowing the acidulated foots to stand to produce an upper fatty acid layer, a bottom water layer, and an intermediate layer, and adding a sufficient quantity of alcohol to said intermediate layer to precipitate phytosterol glucosides.

7. The method of producing glucosides, which comprises subjecting vegetable oil degumming foots to a neutralization treatment, acidulating the foots and heating the same, allowing said acidulated foots to stand to produce an upper fatty acid layer, a bottom water layer, and an intermediate layer containing phytosterol glucoside, and precipitating said glucoside from said intermediate layer.

8. The method of producing glucosides, which comprises subjecting vegetable oil degumming foots to a neutralization treatment, acidulating the foots to a pH of between 2 and 5 and heating the same, allowing the acidulated foots to stand to produce an upper fatty acid layer and a lower layer containing said glucosides, separating said lower layer, and treating said lower

layer with alcohol to precipitate phytosterol glucoside.

9. In the process of producing phytosterol glucosides wherein a vegetable oil is subjected to a neutralization treatment to neutralize the free fatty acid content of the oil and a resulting soapy fraction is acidified, the improvement which comprises allowing the fraction to stand to provide a three-phase mixture having an upper fatty acid layer, a lower water layer, and a middle layer containing phytosterol glucosides, and precipitating phytosterol glucosides from said middle layer.

10. In the process of treating oils containing phytosterol glucosides wherein the oil is treated with an alkaline solution in a quantity sufficient to neutralize the free fatty content of the oil to saponify a portion thereof, and thereafter separating and acidulating the soapy fraction, the improvement which comprises allowing the acidulated fraction to stand to produce an upper fatty acid layer, a bottom water layer, and a middle layer containing phytosterol glucosides and inorganic salts, recovering said middle layer and treating the same with alcohol to precipitate said glucosides and inorganic salts and thereafter washing the precipitates to remove said salts.

11. In the method of producing glucosides in which vegetable oil refinery foots are acidulated, the improvement which comprises allowing said acidulated foots to stand to produce an upper fatty acid layer, a bottom aqueous layer and an intermediate layer, and thereafter separating said intermediate layer and precipitating the same to recover phytosterol glucosides.

12. In the method of producing glucosides in which soybean oil refinery foots have been acidulated to a pH of between 2 and 5 and thereafter heated, the improvement which comprises allowing the acidulated foots to stand to produce an upper fatty acid layer, a bottom layer, and an intermediate layer, and thereafter adding a sufficient quantity of alcohol to said intermediate layer to precipitate phytosterol glucosides.

13. In the method of producing glucosides wherein vegetable oil degumming foots have been subjected to a neutralization treatment and acidulated, the improvement which comprises allowing said acidulated foots to stand to produce an upper fatty acid layer, a bottom water layer, and an intermediate layer containing phytosterol glucoside, and thereafter precipitating said glucoside from said intermediate layer.

14. In the method of producing glucosides in which vegetable oil degumming foots have been subjected to a saponification treatment with an alkali and the foots thereafter acidulated to a pH of between 2 and 5, the improvement which comprises allowing said acidulated foots to stand to produce an upper fatty acid layer and a lower layer containing said glucosides, and thereafter separating said lower layer and precipitating the same with alcohol to precipitate phytosterol glucoside.

DAVID P. LANGLOIS.
